UNITED STATES PATENT OFFICE.

JAMES M. ROSE, OF ALLEGHENY CITY, PENNSYLVANIA.

MANUFACTURE OF WATER-GAS.

SPECIFICATION forming part of Letters Patent No. 370,971, dated October 4, 1887.

Application filed December 27, 1886. Serial No. 222,566. (No model.)

To all whom it may concern:

Be it known that I, JAMES M. ROSE, of Allegheny City, in the county of Allegheny and State of Pennsylvania, have invented a new and useful Improvement in the Manufacture of Water-Gas; and I do hereby declare the following to be a full, clear, and exact description thereof.

My invention relates to the manufacture of what is known as "water-gas," its object being to provide apparatus for the manufacture of this gas especially for fuel and heating purposes, though it is also applicable to the manufacture of illuminating-gas, having for a base the water-gas generated in the apparatus.

To this end my invention consists in arranging around a central steam-boiler a series of gas-generator chambers and lime-chambers, and suitable flues for connecting these chambers and the boiler, so that the waste products of combustion from said generators may pass into the boiler and generate steam therein, and, as some one or more of the series will always be discharging their products into the boiler, a constant pressure of steam is maintained therein, and, as the others of the series are discharging gas through the lime-chambers, a constant supply of gas is obtained from the apparatus.

The invention also consists in arranging lime-chambers around the boiler between said generator-chambers and the boiler and communicating with the generator-chambers; and the invention also consists in having a combustion chamber over the lime-chamber, and communicating at one end with the boiler and at the other end with the generator; and the invention further consists in combining with the generator-chamber a boiler which has outer downtime-flues, a chamber at the bottom, and central uptake-flues, through which the products of combustion pass to generate steam therein, and thence from the uptake-flues to the chimney; and the invention further consists in certain other improvements, all of which will be more fully hereinafter set forth.

To enable others skilled in the art to make and use my invention, I will describe the same more fully, referring to the accompanying drawings, in which—

Figure 1 is a longitudinal section of my im-

proved apparatus. Fig. 2 is a cross-section on the line $x x$, Fig. 1.

Like letters of reference indicate like parts in each.

In the construction of my improved gas-generating apparatus I prefer to employ large generating apparatus, such as shown in the drawings, formed of a series of different gas generating and purifying chambers arranged around a central boiler steam-generator, as by the employment of this form of apparatus I am enabled to operate the method continuously, and I obtain sufficient heat from the waste products of combustion to maintain a sufficient pressure of steam, one or the other gas-generators being always discharging its heated products into and through the steam generator or boiler.

The steam boiler or generator A is placed in the center or centrally of my improved gas-generating apparatus, and arranged either on each side or around the same are the lime-chambers B, while beyond the lime-chambers are the gas-generating or fuel chambers C. The gas-generating chambers are provided with grate-bars c, the ash-pits c' having suitable doors, c'', so that the ash-pit can be closed to prevent the entrance of air from the outside of the apparatus, and extending from the upper end of or above the gas-generator and above the lime-chamber is the combustion chamber or flue d, the products of combustion communicating with the outer flues, a, of the steam-generator A, and passing downwardly through the same into the chamber a', whence they rise through the central series of heating tubes or flues, a'', to the chimney D. The gas-generator C is also provided with the stoking-hole c³ and charging-holes c⁴ in the top wall and c⁵ in the base of the flue d, which can be closed by any suitable blocks or covers, d' d''. The sliding stop-valve d³ is placed at the end of the flue d, so as to close communication between the combustion-flue and steam-boiler during the time the gas is being generated from the incandescent coal.

Communicating with the gas-generator C is the blast-pipe e, said pipe extending upwardly through the outer walls of the apparatus, and having two or more blast-entrances, e', whereby the blast is distributed through the mass of

fuel resting on the grate-bars, and the same is brought to an incandescent state more rapidly and the smoke and other gases more easily driven off therefrom.

5 Leading from the steam-space A' of the steam-generator A are the steam-pipes f, which extend down within the walls of the apparatus and communicate with the different chambers thereof, communicating with the gas-generators near the upper part of the same, as at f', so that the steam can pass through the entire mass of incandescent fuel therein.

The lime-chambers B are separated from the gas-generators C by comparatively thin walls, so that the heat of the combustion of the fuel therein will heat the lime within the chambers B, the lime being further heated by the waste products passing through the flues d over the top of the chambers and by the heat from the boiler, which is separated from the lime-chamber by the thin walls, as at b², the lime within the chambers B being thus kept in a heated or caustic state, so as to act quickly upon any gases passing through the same. The chambers B have the grate-bars b' at the base thereof and the ash-pit b³ below the grate-bars, the ash-pit b³ being, if desired, separated from the ash-pit c' by the removable door or block b⁴; and in order to fill said chamber it is provided with the filling-holes g' g' at the base of the combustion-flue d and above the flue, these holes being closed by removable covers g² g³, so that access can be obtained through these filling-holes directly to the lime-chamber, while the lime within the chamber or the waste products thereof can be withdrawn through the ash-pit b³.

Between the gas-generator C and the lime-chamber B below the grate-bars are suitable ports or openings, h, through which the gas can pass in its course from the gas-generator into the lime-chamber, and at or near the top of the lime-chamber is the gas-outlet h', leading through the walls of the generating apparatus to any suitable reservoir, to conduct away the purified gases. The steam-pipe f extends down within the walls of the generating apparatus, as shown in dotted lines at f', to a point near the base of the lime-chamber B, opening therein at f³, so providing a supply of superheated steam at the base of the lime-chamber, as well as in the upper part of the gas-generator. Air is supplied to the blast-pipe e by any suitable rotary or other blower, and the several pipes or flues are controlled by valves or dampers, as is found necessary.

In order to generate a high heat within the steam-boilers and obtain a full supply of steam, I form the air-ports p in the top wall of the combustion chamber or flue d, these ports being closed by suitable valves or stop-plates, p', and so supply air to the smoke and gases driven off from the partial or slow combustion within the gas-generators, the smoke and other gases burning within said chamber and passing through the flues of the boiler, and I thereby generate a greater heat in the boiler

A, and where it is desired, as in the manufacture of illuminating-gas, generate an exceedingly high heat in the chamber d, which there- 70 by becomes a superheater.

In the manufacture of illuminating-gas I form at the forward end of the superheater or combustion-chamber d a naphtha or oil injector, r, supplied from a suitable pipe or tank, and 75 within the dividing-wall between the generator C and lime-chamber B, I form the pipe or vapor-flue s, extending from the said chamber d to the base of the lime-chamber, so that the oil or naphtha vapor generated within the superheating flue or chamber d will pass down the flue s and rise therefrom through the lime-chamber. At the base of the vapor-flue s is the tar-well t, to receive any tar or other distillates from the oil, and the chamber d has 85 the steam-pipe u, for purposes hereinafter described. To obtain access to the boiler, in which a fire-box may be placed, a section of the surrounding furnace is generally omitted, as at w.

In forming gas by my improved apparatus I fill the gas-generators C with coal or coke, and by means of an air-blast raise the same to a high heat and incandescence, the smoke or waste products of combustion passing from the gas-generators through the chambers or flues d over the top of the lime-chambers B and uniting with the air entering through the ports p, generating a high heat within the chambers, and thence passing downwardly 100 through the tubes or pipes a in the outer portions of the boiler into the heating-space a', thence rising through the several series of pipes or flues, a², to the chimney D, where they escape. The heat generated in the generators by the burning fuel acts to heat the lime chamber by conduction through the walls between the gas-generator and the lime-chamber, and the heat generated within the combustion-chambers d by the more perfect combustion of the smoke and gases acts through 105 the top wall of the lime-chamber B and through the outer walls of the boiler A to further heat the lime-chamber, a large portion of the heat obtained from the burning of the coal within the gas-generator being thus utilized in heating the lime before it is permitted to escape, while the steam necessary for generating the water-gas is thus generated entirely by the waste products from the combustion formed 110 within the generators, and, as a series of generators are employed around the boiler, the necessary heat and pressure of steam can be maintained even though several generators are cut off during the gas-making process. As 115 soon as the coal or coke is brought to the proper state of incandescence, the damper d³, the charging-hole c³, and the valve of the blast pipe e are closed, and steam is admitted to the upper part of the gas generator C 120 through the pipe f', the steam passing downwardly through the mass of incandescent fuel within the chamber and being decomposed 125 by the heat thereof, forming free hydrogen

gas, while the oxygen of the steam unites with the carbon of the fuel, forming carbonic oxide, a portion of oxygen also uniting with some carbonic oxide, forming carbonic acid, 5 while at the same time the sulphur in the coal unites with the heated carbon, forming bisulphide of carbon and some hydrogen sulphide. The resultant gases then pass from the generator C into and upwardly through the body of 10 lime within the chamber B, and as they rise through the same the lime will decompose the bisulphide of carbon, forming hydrogen sulphide, which is subsequently removed by passing the gas through a purifying box containing 15 oxide of iron, and the carbonic acid is converted into carbonic oxide by coming in contact with free carbon deposited in the upper part of the lime-chamber, which resultant gases pass through the outlet h' to the reservoir or the purifying box. In order to obtain 20 a greater portion of hydrogen gas, as soon as the process is commenced I admit steam through the steam-inlet f^3 within the lime-chamber, and this steam is decomposed, the 25 oxygen thereof uniting with the carbonic oxide rising through the lime-chamber, and forming carbonic acid, which in turn combines with free carbon deposited by the products of combustion in the upper part of the lime- 30 chamber and forms carbonic oxide, which, with the free hydrogen gas, passes out from the lime-chamber through the pipe h' , the carbonic oxide generated in the gas-generator thus assisting in generating a further portion 35 of free hydrogen gas within the purifying-chamber. The process is continued until the incandescent coal loses the heat necessary to decompose the steam, which can be determined by the color of the coal, when the steam-sup- 40 ply is cut off, the damper d^3 or charging-hole c^3 and valve in the air-blast pipe e opened, and by means of a blast the coal raised to the proper state of incandescence, when the process is repeated. It can be thus carried on so 45 that a very large portion of gas can be obtained at a low cost, and the apparatus can therefore be employed to advantage in generating gas for fuel and other purposes, the gas obtained being almost entirely free hydrogen 50 and having great heating properties. In order to increase the amount of gas obtained and prevent the chilling of the incandescent fuel, the steam is passed through the heated walls of the apparatus, and is therefore highly sup- 55 perheated before it enters the gas-generator or the purifying-chamber, and consequently the chilling of the incandescent coal or lime is prevented, and the process can be continued for a greater period. 60 When it is desired to make illuminating-gas, the apparatus employed is substantially the same, the combustion-chamber d being employed as a superheating-chamber to vaporize the naphtha or other oil employed to mix 65 the gas, and the form of apparatus shown to the left of the drawings being preferably employed. In such case the charging-hole c^3 is

closed, thereby cutting off communication between the gas-generator and the combustion-chamber d , the stop-valve d^3 between the combustion-chamber and the boiler is closed, and the apparatus is employed in the same manner as required in the generation and production of water-gas. As soon, however, as the generation of this gas is commenced by the 70 admission of steam from the gas-generator, the naphtha or other hydrocarbon is fed from the injector r to the combustion-chamber d , which is highly heated by the more perfect combustion of the smoke and gases therein, 75 and so acts to vaporize and form a fixed gas from the naphtha, the vapor or gas passing down the flue s , which is heated by radiation from the gas-generator and assists in setting the gas, and this gas passing through the lime- 80 chamber B, being intermingled with the other gases formed in the generator C and in the lime-chamber B, the naphtha or oil gas being purified in its course through the lime-chamber, and becoming so thoroughly intermingled 85 with the hydrogen gas passing from the lime-chamber as to form a fixed illuminating-gas of fine quality. The proportion of naphtha or oil gas so formed and mixed with the hydrogen gas can be regulated according to the desired illuminating-power of the resultant gas. 90 At the termination of the gas-making process the valve d^3 is opened and steam is admitted through the pipe u , the steam driving any gas remaining within the chamber d through the 100 boiler-flues to the stack, and the charging-hole c^3 is opened and air-blast turned on, as above described, and the coal raised thereby to incandescence, when the process is repeated. 105 What I claim as my invention, and desire to secure by Letters Patent, is—

1. In a gas apparatus, the combination of a central steam-boiler, a series of generator-chambers and lime-chambers arranged around the same, and suitable flues connecting the generators, lime chambers, and boiler, whereby the heating of the boiler is continued by the products of combustion from one or more sets of generators while the gas is being generated in another set of generators and lime-chambers, substantially as described. 115

2. In a gas apparatus, the combination of a central steam-boiler, a series of lime-chambers arranged around the same, a series of generator-chambers arranged around the lime-chambers, and flues connecting said generators to the boiler and to the lime-chambers, substantially as described. 120

3. In a gas apparatus, the combination of a steam-boiler, A, generator-chamber C, lime-chamber B between said boiler and generator, and a flue or flues connecting said generator and lime-chamber, with a combustion-chamber, d , over said purifying-chamber, and communicating at one end to the generator 125 and at the other to the boiler, substantially as described. 130

4. In a gas apparatus, the combination of a central steam-boiler, a series of lime-chambers

around said boiler, a series of generator-chambers surrounding said lime-chambers, and flues connecting said chambers, with a combustion-chamber above the purifying-chambers, and communicating with the boiler at one end and the generator-chamber at the other, and having an air-inlet therein, substantially as described.

5 5. In a gas apparatus, the combination of a gas-generator, a lime-chamber adjacent thereto, a chamber, *d*, over said lime-chamber, having an oil-injector leading therein, and a gas-flue, *s*, in the division-wall between the generator and the lime-chamber for connecting said chamber *d* to the lime-chamber, substantially as described.

10 6. In combination with gas-generator apparatus, a steam-boiler, *A*, having the outer

downtake-flues, *a*, the chamber *a'* at the base, and the central uptake-flues leading from said space through the steam-space *A'* to the stack, substantially as and for the purpose set forth.

15 7. In a gas apparatus, the combination of a central steam-boiler, a series of lime-chambers and gas-generator chambers arranged around the same, and separate flues for connecting said generator-chambers to the lime-chambers and to the boiler, respectively, substantially as and for the purpose set forth.

20 In testimony whereof I, the said JAMES M. ROSE, have hereunto set my hand.

25 JAMES M. ROSE.
